UNITED STATES PATENT OFFICE.

CLARENCE F. HALL, OF ATLANTA, GEORGIA.

TRACTION ATTACHMENT FOR MOTOR-VEHICLES.

1,325,088.

Specification of Letters Patent. Patented Dec. 16, 1919.

Application filed May 5, 1919. Serial No. 294,680.

To all whom it may concern:

Be it known that I, CLARENCE F. HALL, a citizen of the United States, residing at Atlanta, in the county of Fulton and State 5 of Georgia, have invented a new and useful Traction Attachment for Motor-Vehicles, of which the following is a specification.

This invention relates to a traction attachment for motor vehicles, one of its objects 10 being to provide a simple, durable and efficient device which can be readily stored in the body of the vehicle and which can be applied quickly to the front and back wheels, thus to facilitate the extraction of 15 the vehicle from mud holes and the like.

A further object is to provide an attachment of this character which is readily adjustable to wheel bases of different lengths and to wheels of different diameters.

20 Another object is to provide an attachment which will automatically become disengaged from the front wheel after the completion of one revolution thereof and during the movement of the rear or driving wheel onto 25 the attachment.

Another object is to provide means whereby the device can be applied without the necessity of jacking up the car in order 30 to place the attachment in position there- under.

With the foregoing and other objects in view, which will appear as the description proceeds, the invention resides in the combination and arrangement of parts and in 35 the details of construction hereinafter described and claimed, it being understood that, within the scope of what is claimed, changes in the precise embodiment of the invention shown can be made without de- 40 parting from the spirit of the invention.

In the accompanying drawings the preferred form of the invention has been shown.

In said drawings:

45 Figure 1 is a side elevation of a motor vehicle having the improvement applied thereto and showing the relative positions of the parts before the vehicle is driven forward onto the attachment.

50 Fig. 2 is a plan view of one member of the attachment.

Fig. 3 is a plan view of the other member of the attachment.

55 Fig. 4 is an enlarged section on line 4-4, Fig. 2.

Fig. 5 is a section on line 5-5, Fig. 3.

Fig. 6 is a section on line 6-6, Fig. 2.

Fig. 7 is a plan view of the attaching strap used for connecting one end of the attachment to the front wheel, parts of the 60 strap being broken away.

Fig. 8 is an end view thereof, the ends being removed.

Referring to the figures by characters of reference A designates the rear section of 65 the attachment and B designates the front section thereof. The rear section includes a rope 1 provided with parallel folded portions 2, constituting coupling members, the folds of each member being held together at 70 desired points by wrappings 3 of wire or the like. Eyelets 4 may be interposed between the folds wherever desired they being held in place by frictional engagement with the opposed portions of the rope. A 75 portion of the length of the rope is extended transversely between the members 2, as indicated at 5 and the ends of the rope are extended toward each other and in lapped relation, as indicated at 6, said end 80 portions being flattened and clamped within a metal clip 7, held thereto by rivets or the like. The rope 1 is housed within casings 8 formed along the edges of a strip 9 of canvas or the like, one end of this strip 85 being secured within the clip 7, while the transverse portion 5 of the rope is secured in the other end portion of the strip. Crossed rows of stitches, indicated at 10 may be provided for reinforcing the fabric 90 and, if desired, a bowed strip 11 of spring metal may be extended transversely within the strip 9 so as to hold said strip bowed transversely, it being understood that the clip 7 is similarly bowed. That end portion of the member A nearest the clip 7 is preferably reinforced by an added thickness of fabric indicated at 12 and which extends along the bottom thereof. Ears 13 are provided at the ends of the clip 7 and 100 are pivotally engaged by the ends of chains 14 which can be of any suitable construction. The clip 7 is adapted to be placed transversely upon the tire of the rear wheel W of the vehicle V and the chains 14 are 105 adjustably connected together by means of hooks 15 or the like, so as to hold the clips 7 firmly to the tire as shown in Fig. 1.

The member B includes a single length of rope 15 folded to form parallel members 16 110 preferably wrapped with wire as indicated at 17 and forming terminal eyes 18 in which

are mounted hooks 19. The ends of the rope are lapped and flattened as indicated at 20 and secured within clips 21 from which extend shanks 22 having balls 23 at their outer ends. The rope has an intermediate portion 24 between the members 17 and this intermediate portion as well as the lapping portion 20 and those portions of the rope back of the members 17 are housed within casings 25 formed along the edges of a fabric strip 26 similar to the strip 9. This strip is bowed transversely and, if desired, a transversely bowed cross strip 26' can be slidably mounted on the members 17, this strip having terminal eyes 27 which engage and slide on the members 16.

A bowed strip 28 is adapted to be applied to one of the tires of the front wheels of the vehicle and may be attached thereto by 20 a strap 29 extending between the spokes and adjustably connected together. On this strip is secured an arcuate strip 30 having outstanding socket members 31 so shaped as to receive the ball 23, there being slots 32 in 25 said members for the reception of the pins 22.

In using the device the strip 28 is attached to the front wheel of the vehicle close to and back of its point of contact with the ground. The balls 23 are then inserted into 30 the sockets 31 and the member B of the attachment is placed on the tire of the wheel so as to extend therearound as shown in Fig. 1. The members 17 of the section B are extended to opposite sides of the wheel 35 where it contacts with the ground and the strip 26' is adjusted along said members 16 until it becomes wedged between the tire and the ground. The clip 7 is then attached to the front portion of the rear wheel close to 40 its point of contact with the ground and the two sections A and B are drawn taut and adjustably connected by inserting the hooks 19 into certain of the eyelets 4. With the parts thus applied the rear wheels are 45 rotated slowly. During this operation they will ride onto the sections A attached thereto and, at the same time, pull through the sections B upon the peripheries of the front wheels, causing said front wheels to ride 50 onto the sections B. As the front wheels complete one revolution the balls 23 will pull out of the sockets 31, thus completely detaching the attachment from the front wheels.

55 It has been found in practice that this device constitutes a very efficient means for extracting motor vehicles from mud and the like and is particularly advantageous because it can be applied without the necessity of jacking up the front wheels in order to place the attachment in position. Furthermore, the attachment provides a solid unbroken surface on which the wheels can travel through which the mud will not seep. 60 Likewise this structure will not cut through

the mud and reduce the efficiency of the device as where transverse chains or the like might be substituted for the fabric strips. The adjustable strip 26' is important because it can be positioned tight against the 70 wheel base and thus insure a prompt movement of the front wheel onto the front section as soon as the rear wheel is rotated.

The device can obviously be adjusted to wheel bases of different lengths and, when 75 not in use, the various parts can be disconnected and stored readily.

What is claimed is:

1. A device of the class described including a front wheel engaging section, means 80 for attaching one end thereof to the wheel, means at the other end thereof for straddling the wheel base, a section for attachment to the rear wheel, and means for connecting the two sections. 85

2. A device of the class described including a section for attachment to the rim portion of the rear wheel of a vehicle, a section to be applied to the front wheel, means at one end of the second section for detachably 90 securing said end to the front wheel close to and back of the base thereof, and means at the other end of said section for straddling the base of the wheel and engaging the first 95 named section.

3. The combination with a section for attachment to the rim portion of the rear wheel of a vehicle, of another section, means for connecting one end of the last named section to the front wheel of a vehicle, close 100 to and back of the base thereof, members at the other end of the last named section for straddling the base portion of the front wheel and adjustably connecting said section to the first named section, and means 105 adjustably mounted on said spaced members for wedging between the front wheel and the surface on which it is mounted.

4. A device of the class described including front and rear flexible belt sections, 110 means for securing the rear end of the rear section to the rim portion of the rear wheel of a vehicle, means for connecting one end portion of the front section to the rim of the front wheel of a vehicle, close to and 115 back of the base thereof, spaced members at the other end of the front section for straddling the base of the wheel to which the section is applied, and means for adjustably connecting said members to the rear 120 section.

5. A device of the class described including front and rear belt sections, means for securing the rear belt section to the rear wheel of a vehicle, an attaching member 125 adapted to be secured to the rim portion of the front wheel of a vehicle, means on the front belt section for detachably engaging said attaching member, spaced members extending from one end of the front section 130

for straddling the base of the wheel and adjustably engaging the rear section, and a cross strip adjustably mounted on the spaced members and adjustable to position between the base of the wheel and the surface on which it is mounted.

6. A device of the class described including adjustably connected front and rear sections, each section including a fabric strip, 10 reinforcing means along the marginal portions of the strip, spaced connecting mem-

bers extending from one end of each strip and an attaching means at the other end of each strip.

In testimony that I claim the foregoing as 15 my own I have hereto affixed my signature in the presence of two witnesses.

CLARENCE F. HALL.
